(57) CLAIM

The ornamental design for a yard sign, as shown and described.

DESCRIPTION

FIG. 1 is a left front perspective view of a yard sign which embodies a first embodiment of the present design shown in full lines, the items shown in broken lines are depicted for illustrative purposes only and form no part of the claimed design;

FIG. 2 is a front view of the yard sign;

FIG. 3 is a left side view of the yard sign, the right side view being identical thereto;

FIG. 4 is a back view of the yard sign;

FIG. 5 is a top view of the yard sign;

FIG. 6 is a bottom view of the yard sign; and,

FIG. 7 is a left front perspective view of a yard sign which embodies a second embodiment of the present design shown in full lines, the items shown in broken lines are depicted for illustrative purposes only and form no part of the claimed design.

The support post has been shown broken away in FIGS. 1-4 and 7 to indicate indeterminate length.
